CONTAINER FOR MOTH PREVENTIVE CAKE OR THE LIKE

George C. Irwin, Clayton, and August W.
Willert, Jr., Webster Groves, Mo.

Application January 19, 1950, Serial No. 7,342

Term of patent 14 years

(Cl. D16—2)

To all whom it may concern:

Be it known that we, George C. Irwin and August W. Willert, Jr., citizens of the United States, residing respectively at Clayton and Webster Groves, State of Missouri, have invented a new, original, and ornamental Design for a Container for Moth Preventive Cake, or the Like, of which the following is a specification, reference being had to the accompanying drawing forming a part thereof, in which:

Fig. 1 is a top plan view of a container for moth preventive cake, or the like, showing our new design;

Fig. 2 is a front elevational view thereof;

Fig. 3 is a side elevational view taken from the right side of Fig. 2; and

Fig. 4 is a rear elevational view thereof.

The supporting hook is omitted from Figs. 1 and 4 for convenience of illustration.

The dominant features of our design reside in the portions shown in full lines.

We claim:

The ornamental design for a container for moth preventive cake, or the like, substantially as shown and described.

GEORGE C. IRWIN.

AUGUST W. WILLERT, JR.
